UNITED STATES PATENT OFFICE.

MAURICE ALLAND, OF ATLANTIC CITY, NEW JERSEY.

FOUNTAIN PEN.

Original application filed June 10, 1925, Serial No. 36,104. Divided and this application filed October 3, 1925. Serial No. 60,221.

The object of the invention is to provide several improvements in writing instruments, and particularly in that class quite generally referred to as fountain-pens.

5 Another object is to provide a positive means for filling the reservoir of the fountain-pen with a liquid, which liquid though comprising water in the present instance may be the usual liquid ink of other types 10 of fountain-pens to which this feature of the invention may be applied, said filling means making it possible with a most direct manual operation to expel a maximum quantity of the air from within the reservoir, and 15 consequently upon being released insures the reservoir being filled to a maximum degree with but a single operation, and automatically resets the filling means.

A further object is to provide an improved 20 feed which too can be used in many types of fountain-pens, but which is particularly adaptable for use in the one hereinafter described, said feed comprising an ingeniously designed channel through which air is per- 25 mitted to flow with a maximum degree of freedom past the pen-point and into the reservoir, in order that an uninterrupted flow of water, or liquid ink, as the case may be, can flow steadily from the reservoir, past 30 the inflowing air, and to the pen-point, as the operation of writing with the pen pro- 35 ceeds.

Still another object is to provide broadly 40 for the manufacture of liquid ink in a fountain-pen adjacent to or in the immediate 45 neighborhood of the pen-point, the reservoir of the pen in such case being supplied with water, while entirely outside of the reservoir and in fact close to the pen-point or nib there is positioned a soluble ink pellet, past and in contact with which the water from the reservoir flows and there makes the ink, which is discharged by and from the pen-point, said pellet being so mounted that when dissolved a renewing pellet may be most easily inserted in its stead.

Again, another object is to provide in such a feed member, which when in normal writing position has a transversely extending aperture, a recess in the underside of said member spaced away from said aperture, and a dual holder normally containing ink-making pellets, one portion of said holder extending into and positioning a reserve pellet in said recess, and another por-

tion of said holder extending into and positioning an active pellet in said aperture and exposed to water as it flows from the reservoir past the feed member to the pen, the water upon contacting with said pellet dis- 60 solving the same gradually and causing fluid ink to be made in near proximity to the pen or nib.

And a still further object is to provide as a part of a fountain-pen a novel eraser for 65 removing ink marks from writing paper or other usual types of writing material, said eraser comprising an abrasive "stone," which throughout the following specifications and claims is intended to refer to those mate- 70 rials such as emery, carborundum, stone, pumice, and the like, which in suitable shapes are marketed as sharpening stones for metal tools, than which they are much harder, and which materials are non-wear- 75 ing as compared with paper and the like, such as is used for writing purposes.

With these and other objects in view, the present invention comprises additional novel details of construction and operation herein- 80 after fully brought out in the following de- 85 scription, when read in conjunction with the accompanying drawings, in which Fig. 1 is a side elevation of a fountain-pen comprising one embodiment of the invention, and having one wall of its reservoir section broken away to show the interior thereof; Fig. 2 is a longitudinal section on the line 2-2 of Fig. 1; Fig. 3 is a transverse view on the line 3-3 of Fig. 2; Fig. 4 is a cen- 90 tral vertical longitudinal section of the feed member hereinafter described; Fig. 5 is a transverse section of the same on the line 5-5 of Fig. 4; Fig. 6 is a bottom plan view of the soluble ink pellet-containing mem- 95 ber; Fig. 7 is a side elevation of the same; and Fig. 8 is a side elevation of the feed member; and Fig. 9 is a plan view of the feed member.

Referring to the drawings, the body por- 100 tion of the fountain-pen comprises an an- nular wall 1, surrounding a reservoir sec- 105 tion 2, which is closed at one end 3, and at the other end 4 is externally threaded to re- ceive the correspondingly threaded portion 5 of an annular cap 6, when the pen is not in use, the walls of said cap being provided with air passage-ways 7, and the interior of said cap terminating in one direction in the transversely extending wall 8, beyond which 110

is a magazine 9 adapted to hold a plurality of soluble ink pellets 10.

That portion of the walls of the cap 6 surrounding the outer portion of the magazine 9 is radially reduced at 11 and externally threaded to receive the correspondingly internally threaded portion 12 of a ferrule, which at its free end is provided with a relatively shallow annular flange 13 surrounding an axially positioned aperture, while against said flange and extending through said aperture is positioned a stone 14, formed of suitable material such as emery, carborundum, quarry stone, pumice, and the like, which is adaptable for erasing ink marks from the usual type of writing paper, and with respect to the paper and the usual types of yielding rubber erasers is substantially non-wearing and permanent. The stone itself is provided with an inner flange portion 15, which is firmly secured in operative position between the flange 13 of the ferrule and the free reduced end portion 11 of the walls 6 of the cap.

That end of the reservoir portion opposite to the closure 3 has secured to it in any suitable manner a member 16 provided axially with a bore or throat 17, the inner end portion of the walls of said member being radially reduced at 18 and surrounded by the open end portion 19 of a slender collapsible bag or pouch 20, said end portion being maintained in water and air-tight position by means of a suitable band 21. The outer end portion 22 of the member 16 is formed in any suitable manner exteriorly and is provided with an enlarged axial bore 23, connected with the bore 17 by means of an annular plane shoulder 24 for a purpose hereinafter described.

Extending longitudinally along the outer surface of the bag 20 and upon one side thereof is a relatively inflexible plate 25, to the central portion of which is secured a lug 26, while the opposite end of said lug is provided with an axial bore, and internally threaded at 27 to receive the similarly but externally threaded reduced end portion 28 of an operating member 29, which extends through an aperture 30 in the wall 1 of said reservoir section, and is provided with a sufficiently enlarged head 31 for engagement by the nails of one's thumb and first finger, the outer surface of said wall being notched at 32 so that the finger-nails may be readily positioned beneath the head 31, as will be evident by reference to Fig. 3.

The central portion of the opposite sides of the bag 20 are apertured at 33, and through said apertures extend a pair of interlocking rivets 34, themselves having a central aperture 35 through which the lug 26 is adapted to pass slidably when the head 31 is drawn outwardly manually, and upon being released is again drawn inwardly by

virtue of the resiliency of the walls of said bag.

Normally positioned within the enlarged bore 23 of the member 16 is a so-called feed-member or bar, illustrated in Figs. 2, 4, 5, 8 and 9. This feed-member comprises a body portion 36, which is provided with a normally vertically extending saw-cut 37 in order to provide a passage through which air may pass vertically, as hereinafter described, 75 in entering the throat 17 and bag 20, to relieve the vacuum and permit the fluid to flow from said bag through the throat and to the pen-point or nib 38, the shank 39 of which pen-point embraces the upper side of 80 the otherwise open side of a restricted channel extension 40 of the saw-cut 37, and at its innermost end said pen-point abutting against the shoulder 24 in the member 16.

The cutting of the feed-member provides a 85 bifurcated inner end portion, the opposite walls of which are relatively yielding. When the fountain-pen as an assembled unit is in its normal position for operating, and the feed member is in the position shown in 90 Figs. 2 and 4, the lower free end portion of the channel 40 is gradually tapered at 41, so that there is but a restricted opening of the channel against the under surface of the pen in the neighborhood of the point. 95

The inner wall of the channel 40 is also provided with a central saw-cut 42 in order to permit air to flow upwardly into said channel, and the under portion of said feed-member is provided with an aperture 43, which extends upwardly to the channel 40 and through to the upper surface of the feed-member, and is normally closed at its upper end by the pen-point itself. The feed-member is also provided in its under surface with 105 a recess 44, co-axial with but spaced from the aperture 43, and not extending upwardly sufficiently far to connect with the channel 40.

Referring to Figs. 4, 6 and 7, there will be found a pair of cups having cylindrical sides 110 45, and closed at their ends by means of walls 46, said sides being provided with saw-cuts 47, which when a pellet 10 is dissolved below the upper extent of a cup in the aperture 43, the capillary attraction of the ink for the sides of the cut or slit, serves to impel the liquid through and out of said aperture 43, into the channel 41 and thence to the pen point 38. The opposite end portions 48 of the connecting member 49 are secured in any suitable manner, as for instance by means of rivets 50, to the central portion of each of the walls 46, and these cups thus form a unit which when respectively filled with pellets 10 are insertable in the respective aperture 43 and recess 44, as shown in Fig. 4. When the pellet within the cup within the aperture 43 is dissolved, the pellet-containing unit may be readily removed so that the other cup and its pellet, having been withdrawn from the 125 130

recess 44, may be positioned in said aperture, the empty cup being then positioned within the recess.

In the operation of this device, the pellet-containing member is provided with the soluble ink-pellets from the magazine 9, and said pellets are operatively positioned as shown in Fig. 4 and together with the feed-member are in the respective operative positions shown in Fig. 2, the cap 6, however, being removed by unscrewing the threaded portion 5 from the threads 4, and thereafter placing the cap upon the opposite closed end portion of the body portion of the device.

The head 31 is then manually withdrawn as far as possible until substantially the total length of the bag 20 is compressed against the upper portion of the wall 1 (as viewed in Fig. 2), after which the lower portion 22 of the member 16 is immersed preferably in water or any other suitable solvent for the ink-pellets, the head 31 then being released and the resiliency of the walls of the bag 20 withdrawing the stud 26 and operating member 29 into their innermost positions as shown in Figs. 2 and 3, while in so doing the bag has automatically filled itself with the solvent.

The pen is then withdrawn from beneath the surface of the solvent and is thereafter ready for use in the manner intended, namely, as a writing instrument, for as the pen-point 38 is brought into contact with the writing material and is either manually or otherwise drawn across said material, the solvent by capillary attraction is drawn solely from the reservoir 20 through the throat 17, saw-cut 37, channel 40, and past the soluble ink-pellet 10 in the aperture 43, and thence to the pen-point, where it is discharged upon the writing material in accordance with the manipulations of the pen in writing or otherwise.

In practise, it has been found that it requires approximately two fillings of the reservoir with the desired solvent, in order to dissolve completely the pellet that is operatively positioned in said aperture. When this is done, however, the pellet-containing unit is reversed in position as hereinbefore described and a second pellet is brought into position from the recess 44 in the aperture 43, and the pen is again ready for use, and will continue to be as long as any of the solvent remains in the reservoir and its throat and a portion of the soluble ink-pellets remains in the aperture 43. Obviously, when both pellets have been dissolved, new pellets may be removed from the magazine 9 and placed in said holder for further use of the pen.

It is to be understood that the improved filling mechanism for the reservoir 20 in its broadest sense may be comprised within a fountain-pen not provided with soluble ink-

pellets but which depends upon liquid ink being drawn directly into the reservoir in distinction from the present instance in which only water enters the reservoir, and the ink is manufactured in the immediate vicinity of the point of discharge from the pen-point and as the ink is used.

Furthermore, the feed-member hereinbefore described has been so designed as to permit a steady inward and outward flow of fluid so as to provide a positive supply of ink for the pen and thus eliminating the usual interruptions due to fluid from the reservoir failing to flow by reason of the fact that air is unable to pass inwardly through the feed-member and into the reservoir. Still again, the magazine construction and improved eraser stone above described is adapted for use with many types of writing instruments and not alone with that herein described.

Having thus described my invention, what I claim and desire to protect by Letters Patent of the United States is:—

1. In a fountain-pen, the combination of a barrel having a throat, a feed-bar removable supported by said barrel in said throat and provided with a recess, and a removable holder normally positioned in said recess and adapted to contain a soluble ink-pellet.

2. In a fountain-pen, the combination of a barrel having a throat, a feed-bar removable supported by said barrel in said throat and provided with a recess, and a removable holder normally positioned in said recess and adapted to contain a soluble ink-pellet adjacent to the underside of the pen and exposed to a solvent passing said pellet for discharge by the pen.

3. In a fountain-pen, the combination of a barrel having a throat, a feed-bar removable supported by said barrel in said throat and provided with a transversely extending aperture opening in one direction adjacent to the underside of the pen, a removable holder adapted to contain an ink-pellet and normally positioned in said aperture, said pellet being exposed to a solvent flowing past said aperture before being discharged as liquid ink by the pen.

4. In a fountain-pen, the combination of a pen-supporting member, provided with a transversely extending aperture adapted to contain a soluble ink-pellet and opening in one direction adjacent to the underside of the pen and in the other direction opening on the normal underside of said member, said member being also provided with a recess in its normal underside spaced from said aperture, and a dual holder, having a portion adapted to contain an ink-pellet and extending into said aperture in order to expose the pellet to a solvent flowing past the upper portion of said aperture before being discharged as liquid ink by the pen,

and said holder having another portion

adapted to contain a reserve pellet and extending into said recess in order to protect and maintain said reserve pellet in dry condition.

5. In a fountain-pen, the combination of a pen-holding member, provided with a transversely extending aperture and a recess having spaced parallel axes, a pair of receptacles adapted to contain soluble ink tablets and normally positioned, one in the aperture and a reserve one in the recess, and means connecting said receptacles together to form a unit, said unit being removable and reversible in order to place the reserve pellet in the aperture and the other receptacle, from which the pellet has been dissolved, in the recess.

6. In a fountain-pen, the combination of a barrel having a throat, a feed-member normally positioned within said throat and operatively positioning a removable pen-point, a recess in said feed-member, and a removable holder for an ink-pellet normally posi-

tioned within said recess and operatively positioning a replaceable soluble ink-pellet 25 adjacent to the underside of the pen-point.

7. In a fountain-pen, the combination of a barrel having a throat, a feed-member normally positioned within said throat and operatively positioning a removable pen-point, 30 a plurality of recesses in said member, one of which opens adjacent to said pen-point, and a holder for soluble ink-pellets normally positioning such pellets in said recesses, the pellet in the recess opening as 35 specified being exposed to an ink solvent passing thereby to make ink for the pen-point to discharge, and the pellets in the remaining recesses being protected from said solvent and held in reserve, whereby removal 40 and repositioning said holder operatively positions one of said reserve pellets in said specified recess.

In testimony whereof I have affixed my signature.

MAURICE ALLAND.
